HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

FILLING-REPLENISHING-LOOM BOBBIN CLEANER.

Application filed April 14, 1927. Serial No. 183,847.

This invention relates to filling replenishing looms and more particularly to the bobbin cleaner attachments of such looms, whereby the discharged filling carrier is 5 cleaned of waste yarn thereon during the loom operation.

In that type of filling replenishing looms wherein the filling carrier or bobbin in the shuttle is changed to effect replenishment, 10 there remains upon the ejected filling carrier or bobbin an amount of waste yarn which must be removed before the filling carrier or bobbin can be again supplied with filling. It is important, therefore, that each 15 of the filling carriers or bobbins ejected from the shuttle during replenishment shall have the waste yarn cleaned therefrom, and to insure that successive filling carriers or bobbins ejected from the shuttle shall not pass 20 from the bobbin cleaning attachment prior to being cleaned, the present invention provides means for holding the bobbin in bobbin cleaning position with its upwardly extending filling in contact with the bobbin cleaner and on replenishment of filling to trip the 25 bobbin holding means for the discharge of the cleaned filling carrier and then quickly return the same to its initial position that the incoming filling carrier to be cleaned 30 shall be arrested in bobbin cleaning position and not be permitted to pass from the bobbin cleaning attachment until it has been cleaned. To effectively carry out the purposes of the invention, a tripping device is 35 provided for the bobbin holding means and provision is made for adjusting the tripping device so that the bobbin holding means will release the cleaned filling carrier during a part of the replenishing operation and permit the bobbin holding means to return to its 40 bobbin holding position before the completion of the replenishing operation, with the result that the incoming filling carrier to be cleaned will be arrested for the operation of 45 the cleaning device.

The invention and new combination of parts and novel features thereof will best be made clear from the following description and the accompanying drawings of one 50 good form of the invention.

In the drawings:

Fig. 1 is a perspective view with some of the parts broken away, showing a filling re-

plenishing loom with the present invention associated therewith; 55

Fig. 2 is a perspective view with parts broken away, showing the action of the tripping device on replenishment of filling;

Fig. 3 is a sectional detail longitudinally through the bobbin cleaner and its associated 60 parts; and

Fig. 4 is a section on the line 4-4 of Fig. 3.

The loom frame 1 may be of usual construction and mounted on the breast beam 2 65 is the magazine or hopper stand 3, the rotary portion of which carries a number of filling carriers 4 which are successively moved to filling replenishing position. Extending from the hopper stand 3 is the pin 70 or stud shaft 5 on which is mounted the transerrer 6 having its downwardly extending arm 7 connected with a dog 8 adapted to be engaged by a bunter on the lay to effect replenishment of filling. These parts are or 75 may be of usual character and need no further explanation as they are now well understood in the art.

Secured to the loom frame 1 is the bracket 9 which supports the bobbin receiver 10 80 which has an open bottom 11, and below the bottom of the receiver is the bobbin can 12 into which the cleaned bobbins are discharged.

Extending transversely through the bobbin receiver 10 is the cleaning shaft 13, on one end portion of which is a pulley 14 which may be driven by a belt 15 actuated by some going part of the loom, as, for instance, the lower or cam shaft 16. In the present instance, the cam shaft 16 is provided with the pick cam 17 and on the hub of the latter is the pulley 18 about which the belt 15 passes and by which the bobbin cleaner is rotated during loom operation. Mounted on 90 the bobbin cleaner shaft 13 is the bobbin cleaner 19 provided with a roughened surface which may be formed as a series of pins 20 for withdrawing or unwinding the upwardly extending portion *a* of the filling 100 from the bobbin 21 which is supported below the bobbin cleaner for this purpose.

The bobbin positioning means comprises a bobbin support 22 which is secured to a shaft 23 extending transversely of the bobbin receiver, and a spring 24 normally acts 105

upon the bobbin support 22 to maintain it in its raised or bobbin supporting position. The bobbin support 22 is preferably inclined below the bobbin cleaner 19 and its 5 lower end portion cooperates with a stop which limits the upward swinging movement of the bobbin support 22 under the actuation of its closing spring 24. In the present instance of the invention, the stop 10 comprises a downwardly inclined bobbin deflector 25, and lower end portion of which is connected by a projection 26 with the bobbin receiver, and the lower end portion 15 of the bobbin support 22 is adapted to engage the projection 26 or lower edge of the bobbin deflector to normally close the space between them and maintain the bobbin, as 21, Fig. 1, in bobbin cleaning position.

Above the bobbin support 22 is the bobbin 20 stop 27 against which the incoming bobbin may contact when it is ejected from the shuttle. The bobbin stop 27 may be variously contrived, but in the present case it is formed of canvas and at its lower end is 25 supported by a rod 28 extending transversely of the bobbin receiver 10, and at its upper end is similarly supported by a rod 29, each of which rods may appropriately engage a loop formed in the canvas at each end.

The rod 23 to which the bobbin support 22 is secured extends through a side of the bobbin receiver 10 and is provided on the outer end thereof with a crank arm 30, the upper end portion of the arm 30 being provided with the outwardly extending portion 31.

The transverse or change shaft 32 is mounted on the front portion of the breast beam, as usual in filling replenishing looms, 40 and has secured thereto the downwardly extending arm 33 to which is adjustably connected at its lower end the trip arm 34, which may be secured in adjusted position relative to the arm 33 by means of a set 45 screw 35. The laterally extending portion of the trip arm 34 has a downward projection 36 which extends frontwardly of and is out of engagement with the crank arm on the shaft 23.

On replenishment of filling when the transverse or rock shaft 32 is rocked, the 50 downwardly extending portion of the trip arm 34 moves towards and then engages the arm 31 and thereby rocks the bobbin support 22 in a downward direction to discharge the cleaned filling carrier previously supported thereby. On continued operation of the replenishing mechanism, the arm 36 moves frontwardly and is freed from the 55 arm 31 of the bobbin support prior to the completion of the replenishing operation, the effect being that the spring 24 will close the bobbin support to its initial position before the incoming filling carrier or bobbin reaches 60 the bobbin support and thereby arrests the 65

incoming bobbin to be cleaned in bobbin cleaning position.

The trip mechanism for the bobbin support acts first to discharge a cleaned filling carrier, and before the replenishing operation is completed the trip mechanism frees the bobbin support to the action of its spring 24, so that it closes before the incoming filling carrier arrives in bobbin cleaning position. In Fig. 2 the incoming filling carrier is shown as just entering the bobbin receiver, and it will be noted that the trip mechanism is now in action to lower the bobbin support 22 for the discharge of a cleaned filling carrier, and on the reverse movement of the transverse shaft the parts of the trip mechanism will be disengaged to permit the bobbin support 22 to move into contact with the bobbin deflector and close the exit or discharge passage.

In order that the desired action may be accomplished, the trip arm 34 is adjustably secured to the arm 33, so that the timing can be regulated to effect the interception of the incoming bobbin before it reaches bobbin cleaning position.

As hereinbefore stated, the bobbin cleaner 19 is mounted on the shaft 13 and is secured to said shaft by a yielding clutch connection which may be disengaged by endwise movement of the bobbin cleaner. The clutch comprises a series of fingers 37, Fig. 3, about which passes a contractile spring 38, and the end portion 39 of the bobbin cleaner is formed to engage between the spring actuated arms 37 by pushing endwise upon the bobbin cleaner, and, conversely, the bobbin cleaner may be removed from the shaft 13 endwise by a reverse pull upon the bobbin cleaner.

Secured to the bearing 45 of the shaft 13 is a clutch guard 40, Fig. 3, which extends through the side wall of the bobbin cleaner and overlies the clutch, thereby preventing yarn from being wound upon the clutch or interfering with its proper operation as hereinbefore described. The guard 40 may be appropriately secured to the bearing 45 by a set screw 41 which passes through the hub portion of the guard, as indicated in Fig. 3.

The opposite side wall of the bobbin receiver is provided with an opening 42 which is normally closed by the flange 43 on the guard 44 which encircles the outer end portion of the bobbin cleaner. By endwise removal of the guard 44, the bobbin cleaner 19 may be removed endwise from its clutch connection with the shaft 13 and permit the yarn which has been wound thereon to be stripped from the bobbin cleaner.

The trip mechanism for the bobbin support 22 affords a simple and effective means for impulsively opening the bobbin support for the discharge of a cleaned filling carrier

and permits its closure prior to the completion of the replenishing operation to thereby intercept and insure that the incoming filling carrier shall not pass from the bobbin cleaning attachment before it has been cleaned.

What is claimed is:

1. In a filling replenishing loom, the combination of replenishing mechanism, a bobbin receiver having a bobbin cleaner mounted in the upper part of the receiver, a pivotally mounted bobbin support below the bobbin cleaner for supporting a bobbin to be cleaned that the upwardly extending filling may engage the bobbin cleaner, a spring normally acting to maintain the bobbin support in bobbin cleaning position below the cleaner, and a trip mechanism disconnected from the bobbin support and actuated on replenishment of filling to first engage and trip the bobbin support and discharge a cleaned bobbin and then free the bobbin support to the action of its spring before the completion of the replenishing operation that an incoming bobbin to be cleaned may be intercepted and prevented from discharge before it is cleaned.

2. In a filling replenishing loom, the combination of replenishing mechanism, a bobbin receiver, a rotary bobbin cleaner mounted in the receiver, a bobbin positioner below the bobbin cleaner comprising a bobbin deflector and a pivoted bobbin support between which a bobbin is held for cleaning purposes, a spring acting on the bobbin support for normally closing it and holding it in closed relation to the deflector, and a trip mechanism unconnected with the bobbin support and actuated on replenishment of filling to move into engagement with and separate the support from the deflector to permit the discharge of a cleaned bobbin and then disengage the support to permit the spring to close the bobbin support and deflector prior to the completion of the replenishing operation.

3. In a filling replenishing loom, the combination of replenishing mechanism, a bobbin receiver having a bobbin cleaner, a pivotally mounted bobbin support below the bobbin cleaner for holding a bobbin that the upwardly extending filling end may engage the bobbin cleaner, an arm extending from the bobbin support, a change shaft having an arm unconnected with the arm of the bobbin support and normally separated frontwardly thereof until call for replenishment of filling and thereupon being first moved into engagement therewith to discharge a cleaned bobbin and then out of engagement therewith before completion of the replenishing operation, and a bobbin support closing spring which effects closure of the bobbin support before completion of the replenishing operation.

4. In a filling replenishing loom, the com-

bination of replenishing mechanism, a bobbin receiver having a bobbin cleaner, a pivotally mounted bobbin support for positioning a bobbin to be cleaned below the bobbin cleaner, a crank arm on the pivotally mounted bobbin support, a transverse or change shaft, an actuator extending therefrom normally frontward of and out of contact with the crank arm on the bobbin support and constituting with the crank arm on the bobbin support a trip for moving the bobbin support to discharge a cleaned bobbin on replenishment of filling and then becoming disengaged therefrom prior to the completion of the replenishing operation, and a spring for returning the bobbin support to bobbin supporting position when freed from the actuator and before the change or transverse shaft has assumed its initial position.

5. In a filling replenishing loom, the combination of replenishing mechanism, a bobbin receiver having a bobbin cleaner, a pivotally mounted bobbin support for positioning a bobbin to be cleaned below the bobbin cleaner, a crank arm on the pivotally mounted bobbin support, a transverse or change shaft, an actuator extending therefrom normally out of contact with the crank arm on the bobbin support and constituting with the crank arm on the bobbin support a trip for moving the bobbin support to discharge a cleaned bobbin on replenishment of filling and then becoming disengaged therefrom before completion of the replenishing operation, a spring for returning the bobbin support to bobbin supporting position when freed from the actuator and before the change or transverse shaft has assumed its initial position, and means for relatively adjusting the crank arm and actuator to vary the time of opening and closing movements of the bobbin support.

6. In a filling replenishing loom, the combination of a bobbin receiver, a bobbin cleaner shaft, means for rotating the shaft, a bobbin cleaner having a detachable clutch connection with the shaft, a guard for the clutch connection extending into the bobbin receiver and protecting the clutch connection from contact with the yarn as it is unwound from the bobbin being cleaned.

7. In a filling replenishing loom, the combination of a bobbin receiver, a bobbin cleaner shaft, means for rotating the shaft, a bobbin cleaner having a detachable clutch connection with the shaft, a guard for the clutch connection extending into the bobbin receiver and protecting the clutch connection from contact with the yarn as it is unwound from the bobbin being cleaned, and a guard for the opposite end of the bobbin cleaner.

8. In a filling replenishing loom, the combination of a bobbin receiver, a bobbin cleaner shaft, means for rotating the shaft, a bobbin cleaner, a spring acting clutch for

connecting the bobbin cleaner and its shaft by endwise movement of the bobbin cleaner, a guard extending into the bobbin receiver and protecting the clutch from contact with the yarn as it is withdrawn from the bobbin being cleaned, and a detachable guard extending into the bobbin receiver at the oppo-

site end of the bobbin cleaner that the bobbin cleaner may be removed endwise through the bobbin receiver when the detachable guard is withdrawn. ¹⁰

In testimony whereof, I have signed my name to this specification.

HARRY A. DAVIS.
